UNITED STATES PATENT OFFICE.

HANS O. C. ISENBERG, OF NEW YORK, N. Y., AND WALTER PIERNAY, OF STETTIN, GERMANY, ASSIGNEES TO UNIVERSAL INCINERATOR CORPORATION, A CORPORATION OF DELAWARE.

CHARGING APPARATUS FOR FURNACES AND THE LIKE.

Application filed November 21, 1924. Serial No. 751,276.

Our invention relates to improvements in feed chutes such as are adapted to feed broken or divided material such as coal. The invention is intended to provide a simple and reliable means for controlling the amount of material flowing through the chute, and for delivering definite amounts of the material to the furnace or other point of delivery at desired times. The invention is also intended to provide a series of succeeding closures through which the material passes which will operate successively so that one closure will be closed before another is opened beneath it, and thus the chute serves as a seal to prevent the escape of gases. The invention also includes certain details which will be described for nicely regulating the flow and delivery of material through the chute.

Before proceeding to describe the specific construction of the improved feeding apparatus, we desire to have it understood that changes in the form, proportion, size, and minor details may be made within the scope of the claims without departing from the spirit or sacrificing any of the advantages of the invention.

In the accompanying drawings forming a part of this specification we have shown a single embodiment of our invention by way of example.

Figure 1 is a vertical section of the feeding chute or charging duct equipped with the new devices.

Figure 2 is an elevation thereof.

Figure 3 is a sectional view similar to Figure 1 with some of the movable or operating devices in a different position.

Figure 4 is an elevation similar to Figure 2 but seen from the opposite side.

Figure 5 is a horizontal section taken on the line A—B of Figure 4 at a somewhat larger scale, and

Figure 6 is a horizontal section taken on the line C—D of Figure 4 likewise in a somewhat larger scale.

In the embodiment shown, the material is supplied in any suitable manner to the funnel 1 of the feeding chute, and a horizontal

sliding plate 2 is provided in connection with the funnel 1 for the purpose of controlling the supply, that is to say, regulating the amount of the supplied material as desired. To this end the sliding plate 2 may be adjusted or positioned by means of a hand wheel 2^a at the outer end of an adjusting spindle 2^b, as will be readily understood on inspection of Figure 1. Close below the slide a depending plate or flap 3 is pivotally mounted in the funnel, and a hand lever 3^a is keyed to the outer end of the one trunnion of the flap 3 for setting purposes, so that the latter can be given any desired inclined position in order to properly guide the material from the funnel into the drum 4. At the same time the filling degree of the drum also depends upon the setting of the flap 3.

As hereinbefore stated the drum 4 is divided by means of radial partitions 4^a into a number of compartments 4^b. As shown in the example of Figure 1 there are four compartments 4^b provided, but it goes without saying that any other appropriate number of compartments may be chosen to comply with any particular requirement. The direction of rotation of the drum is denoted by an arrow.

The uppermost chamber 6 of the chute with the drum 4 mounted therein is open at the bottom, but the opening is normally held closed by the plate or door 5 keyed to a shaft 5^a duly supported in bearings in the wall of the chamber 6^a next below. Firmly attached to the outer end of the shaft 5^a is an arm 5^b carrying an adjustable weight 5^c in order to normally hold the plate 5 in its closed position, as shown in Figure 1, that is to say, with its upper surface in contact with the wall 8 of the chamber. It will be seen that when a load of material is deposited upon the plate 5, and such load is sufficient to overcome the action of the duly overbalanced counter-weight 5^c, the plate 5 will turn downwards to drop the material into the chamber 6^a, as shown in Figure 3, but immediately thereupon the plate 5 will return to its normal or closing position.

A closing plate or door 7 of similar construction comprising a shaft 7^a and an adjustable weight 7^b mounted on an arm 7^c is provided at the bottom end of the chamber 6^a. In a like manner the overbalancing weight 7^b is adjusted to normally hold the plate 7 in its closed position as shown in Figure 1, and to turn the plate down into the position shown in dotted lines in Figure 3, as soon as the whole of the charge or load of material discharged from the upper plate 5 will have been deposited thereon. The material is thus delivered to the lowermost chamber 6^b of the chute whence it will further drop into its place of destination.

Preferably the lower plate or door may be displaced or positioned in a direction opposed with respect to that of the upper plate 5, as will be seen in Figure 1, so that the material dropping from the upper plate 5 will strike upon the plate 7 at a point near the axis of rotation of the latter.

The continuous movement of the feeding drum 4 may be accomplished by means of a belt drive, a chain gearing or a toothed gearing, in any suitable manner. Figures 4 and 5 illustrate an arrangement for intermittent rotation of the drum. In this modification the drive comprises an eccentric 9^a with a rod 9 connected with a bell crank lever 10. The horizontal arm of the latter is connected by means of a rod 11 with two parallel discs 12—12^a, loosely mounted on the shaft 14 carrying the drum 4 and duly supported in bearings provided in the walls of the chute, so that the movement of the eccentric 9^a will cause the two discs 12—12^a to rotate. Intermediate between the latter a toothed wheel 15 is keyed to the shaft 14 which also carries the drum 4, and a pawl 13 is provided between the two discs on a pin firmly connected with the latter. As will be seen in Figure 4, the two discs 12 and 12^a are of a larger diameter than the wheel 15 so that the pawl 13 will always be in engagement with the toothed circumference of the latter.

As the movement of the eccentric 9^a causes the toothed wheel 15 to intermittently rotate, through the agency of the bell crank lever 10, the rod 11, and the discs 12—12^a with the pawl 13 therebetween, the drum 4 will at the same time be rotated accordingly at intervals. The pawl 13 and the co-operating wheel 15 obviously are actuated and work in the usual manner of a pawl and ratchet wheel arrangement, to intermittently or step-wise feed the wheel 15 and the drum 4 forward. It will be noticed by reference to Figure 1 that the wall 8 of the chamber 6 extends well down into the chamber 6^a forming a discharge spout, and the corresponding wall of the chamber 6^a extends similarly down into the chamber 6^b. This prolongation of the lower ends of the chamber walls

gives them the function of a spout so as to 65 form a concentrated discharge, and the said ends also make a suitable seat for the closing plates 5 and 7.

We shall now proceed to describe the operation of the charging apparatus. 70

The material supplied to the funnel 1 in any appropriate manner descends towards the drum 4 between the wall of the funnel and the properly adjusted guiding plate or flap 3. Owing to the rotation of the drum 75 4 the material deposited in any of the compartments 4^b of the drum is discharged therefrom on the opposite side, with respect to the filling side, into the chamber 6 and accumulates on the bottom plate 5. As soon so as the discharge and accumulation is finished, the plate 5 reaches a weight in excess of the counter-balancing weight 5^b of the plate, that is to say constitutes a charge or load of a certain predetermined weight, in 85 accordance with the adjustment of the weight 5^b, and the plate 5 will turn about its pivot or axis 5^a and drop the load into the chamber 6^a, whereupon the plate 5 will return to its normal or closing position. At the same 90 time the lower plate or door 7 begins to open under the weight of the received load and discharges the material into the lowermost chamber 6^b. This done, the plate 7 also returns to its normal or closing position, while 95 the material drops into the furnace or the like in order to undergo a treatment or to act as desired.

The distance between the two plates 5 and 7 and the overbalance of the weights 5^b and 7^b respectively, may be chosen in a manner that the chute will always be closed by at least the one or the other plate in order that, at each charging period or at predetermined intervals, only the load of a single compartment of the drum 4 will be fed to the furnace or the like. In case of combining the feeding apparatus with a furnace or plant in which chemical processes are carried out that do not allow the admission of air through 110 the chute or develop useful or injurious gases which ought not to be permitted to escape through the chute, the particular construction of the apparatus will also comply with these requirements, that is to say, at least 115 one closing plate will be shut at any time during operation to always hold the chute closed.

As above described, the closures or plates 5 and 7 are operated by gravity and closed 120 by the weight, but it is better to have the closure plates operated intermittently but positively at predetermined intervals. To this end the shaft 7^a has a crank 19 connected by a rod 18 with an arm 17 pivotally mounted in the wall of the chute and the lever 5^c is connected by a rod 21 with a similar arm 20. On the other hand there are three dogs

or cams 16 keyed to the outer end of the drum shaft 14 which at each rotation will cause the cams to turn the arms 17 and 20 intermittently and to thereby raise the levers 5° and 7° in order to open the plates or doors 5 and 7 respectively. Thus the latter are opened positively and closed by the action of the weights 5^b and 7^b respectively.

If for any reason it is desired to have the closure plates 5 and 7 operate by gravity, this can be done by simply removing the connecting rods 18 and 21 from the arms 17 and 19 and 20 and 5° respectively. Thus it will be seen that without any modification the drum and closure plates can operate in desired sequence, and either positively or by gravity.

As shown in Figures 4 and 5 the connection of the rod 11 with the horizontal arm 20 of the bell crank lever 10 is adjustable so that at each stroke of the rod the wheel 15 will be revolved for a certain predetermined number of teeth in accordance with the adjustment made. In this manner the rotary speed of the drum 4 may be increased or reduced.

It will be seen that the arrangement described acts as a seal because when a deposit from one of the compartments of the drum 30 has dropped on the closure 5 and passed through, said closure will return to its closed position before the weight of the material 35 opens the closure 7, and as these closures act successively, and as the drum also in connection with the incoming fuel acts as a seal, the backflow of gases through the chute is prevented.

Though we have described with great particularity of detail a specific embodiment 40 of our invention, yet it is not to be understood therefrom that the invention is limited to the particular embodiment disclosed. Various modifications in detail and in the arrangement and combination of the parts 45 may be made by those versed in the art, without departure from the invention.

We claim:—

1. A feeding chute for divided material, comprising in combination a rotary feeding 50 drum, a pawl and ratchet device in operative connection with the drum, means for actuating the said device to impart stepwise motion to the drum, a chamber located below said drum, a plate at the bottom of said chamber, a second chamber below the first denoted chamber, a plate at the bottom of said second chamber, and means for positively operating the two plates in succession at predetermined times and in accordance 55 with the intermittent movements of the drum, substantially as and for the purpose set forth.

2. A feeding chute for divided material, comprising in combination a rotary feeding 60 drum, means for intermittently imparting

rotary motion to the drum, a chamber located below the drum, a hinged plate at the bottom of the chamber, a second chamber below the first stated chamber, a hinged plate at the bottom of the said second chamber, means adapted to normally hold said plates closed, a shaft carrying the drum, cams keyed to the shaft, and pivoted arms connected through rods and suitable intermediate means with the said plates and adapted to be operated by said cams to open the plates intermittently in succession at predetermined times in accordance with the movements of the drum, substantially as set forth. 70

3. A feeding chute comprising a series of superposed chambers, the wall of the chamber above projecting downward into the chamber below to form a spout, swinging closure plates for the lower ends of the chamber walls, and regulatable means for feeding material into the uppermost chamber. 80

4. In a feed chute, in combination, a plurality of superposed chambers, a swinging closure plate at the lower end of each of said chambers, a rotatable drum in the upper chamber having compartments to regulate the feed through the chambers, a drum shaft for said drum, cams on the drum shaft, and connections between the cams and the closure plates disposed to operate the said plates in succession. 90

5. A feeding chute comprising a series of superposed chambers discharging from one into the other, a rotatable drum in one of said chambers having compartments to regulate the feed through the chambers, regulatable means for feeding material into the uppermost chamber, and swinging closure plates for the lower ends of the chambers, said closure plates being disposed so that the upper will discharge its load upon and near the axis of the one beneath. 100

6. Means for feeding fuel comprising a feeding chute, a rotatable drum therein, means for rotating said drum, a plurality of swinging closure plates in said chute, and means connected to and operated by said drum rotating means for swinging said closure plates. 110

7. Means for feeding fuel comprising a feeding chute, a rotatable drum therein, means for rotating said drum, a plurality of swinging closure plates in said chute, and means connected to and operated by said drum rotating means for swinging said closure plates successively. 120

8. Means for feeding fuel comprising a feeding chute, a rotatable drum therein, means for rotating said drum, a plurality of swinging closure plates in said chute, and means connected to and operated by said drum rotating means for swinging said closure plates successively, said closure 130

plates being so disposed that the upper will discharge its load upon and near the axis of the one beneath.

9. A fuel feeder comprising a casing having a lower chamber with a discharge opening and an upper chamber with a discharge portion opening into the lower chamber, valves for opening and closing said openings, actuating members connected to the 10 valves, a cam acting alternately upon said members to operate the valves, a rotary feed

device for delivering material to the discharge portion of the upper chamber, a reciprocating actuator, and means operated by the actuator for rotating said cam and 15 said feed device.

In testimony whereof, we have signed our names to this specification this fifth day of November, 1924.
